UNITED STATES PATENT OFFICE.

OLIVER McCARTHY, OF MERIDEN, CONNECTICUT, ASSIGNOR TO THE
MERIDEN BRITANNIA COMPANY, OF SAME PLACE.

DESIGN FOR A COFFIN-PLATE.

SPECIFICATION forming part of Design No. 21,508, dated April 26, 1892.

Application filed March 28, 1892. Serial No. 426,825. Term of patent 7 years.

To all whom it may concern:

Be it known that I, OLIVER McCARTHY, of Meriden, in the county of New Haven and State of Connecticut, have invented a new Design 5 for Coffin-Plates; and I do hereby declare the following, when taken in connection with accompanying drawing, to be a full, clear, and exact description of the same, and which said drawing constitutes part of this specification, 10 and represents a face view.

This invention relates to a design for coffin-plates, with special reference to the name-plate or to the handle-plate; and the design consists in the configuration and ornamentation as shown in the accompanying illustration. 15

The body of the plate presents a surface in the form of a parallelogram. Around the body is the representation of a border, presenting a convex surface, ornamented by a 20 series of scallops, with the representation of tongues springing from between the scallops

and branching to the right and left to the edge of the plate, as shown in the accompanying illustration.

It will be understood that the name-plate and handle-plate are the same, except that the handle-plate will be provided with sockets, such sockets being represented by broken lines in the illustration; but this construction is immaterial to the design, the outline and ornamentation of the plate being the same in either case.

I claim—

The design for a coffin-plate, herein described, as shown in the accompanying illustration.

In testimony whereof I have signed this specification in the presence of two subscribing witnesses.

OLIVER McCARTHY.
